No. 801,941.

S. W. WARDWELL.

PATENTED OCT. 17, 1905.

CONTROLLING MEANS FOR WINDING MACHINES.

APPLICATION FILED JUNE 4, 1904.

UNITED STATES PATENT OFFICE.

SIMON W. WARDWELL, OF PROVIDENCE, RHODE ISLAND, ASSIGNOR TO
UNIVERSAL WINDING COMPANY, OF PORTLAND, MAINE, A CORPORA-
TION OF MAINE.

CONTROLLING MEANS FOR WINDING-MACHINES.

No. 801,941.

Specification of Letters Patent.

Patented Oct. 17, 1905.

Application filed June 4, 1904. Serial No. 211,203.

To all whom it may concern:

Be it known that I, SIMON W. WARDWELL, a citizen of the United States, residing at Providence, in the county of Providence and State 5 of Rhode Island, have invented new and useful Improvements in Controlling Means for Winding-Machines, of which the following is a specification.

My invention relates to winding-machines, 10 and particularly to the means for controlling their operation.

The object of my invention is to provide improved devices for starting the machine and for stopping it automatically upon the break- 15 age of the supply or at the finish of the cop.

The invention is fully set forth in the following specification, illustrated by the accompanying drawings, in which—

Figure 1 is a front view of the winding-machine, showing the relation of the starting and stopping mechanism; Fig. 2, an enlarged detail view of the braking device; Fig. 3, a detail view of the stopping-lever; Fig. 4, an enlarged sectional view on the line 11, Fig. 1; 25 Fig. 5, a detail view of the threading-guide, showing its relation to the stopping-lever.

The machine in general is of a familiar type known to those versed in the art as the "Universal winding-machine."

30 The main frame A supports bearings for the winding-spindle B and cam-shaft C, the latter carrying the cam (not shown) which reciprocates the thread-guide D. The thread-guide is carried in the traverse-frame E, the latter being pivoted on the cam-shaft C to swing to 35 allow the guide to move away from the winding-spindle as the cop is built up thereon. The devices shown at G and described in my pending application, Serial No. 135,768, filed 40 December 18, 1902, serve to apply pressure on the traverse-frame E to resist the outward movement of the guide, and to prevent this pressure forcing the guide back toward the spindle a detent is provided on the frame 45 E. I prefer to make this detent in the form shown and described in my pending application, Serial No. 211,204, filed June 4, 1904, in which an arm e, operated by a spring-pressed finger-lever f, engages a V-shaped groove in 50 the sector H through its wedge-shaped extremity e.

The sector H is pivoted at h on the main

frame A and besides serving as a track for the arm e to bear on performs the additional function of a detent for the starting-lever J when 55 the latter is thrown into position to start the machine. The lever J is mounted on a rock-shaft j, the latter extending to the back of the machine and connected to engage the driving mechanism. For this latter any usual device 60 may be used, preferably that shown and described in my pending application, Serial No. 211,205, filed June 4, 1904. With this arrangement the driving-pulley is thrown in and out of engagement with a suitable clutch on 65 the spindle B by a rock-lever on the shaft j. The rock-shaft j is operated by any suitable spring arrangement to turn in the direction indicated by the arrow, Fig. 1, to release the driving-pulley from the clutch. For operat- 70 ing the rock-lever I have preferred to show a lever s, fastened to the rear end of the rock-shaft j and connected by a coiled spring t to the machine-frame. Another suitable arrangement would be to provide a coiled spring 75 on the rock-shaft, held under torsion by having one end fast in the frame and the other secured to the shaft. To engage the driving-pulley with the clutch, the shaft is rocked in the opposite direction by means of the starting- 80 lever J, and the shaft is held in this position (see Fig. 1) by the arm l, engaging the extension h' of the sector H. The arm l extends from the hub of the lever J and is formed at its lower extremity with a lug l', engaging a 85 shoulder h² on the extension of the sector H. Beyond this shoulder is a bearing-surface h³, which rests on the lug l' when the latter has been released from the shoulder h², so that the sector H is always supported at its free 90 end by the arm l. The weight of the sector maintains the lug l' and shoulder h² in engagement, and when it is desired to stop the machine it is only necessary to raise the free end of the sector to release the arm l and allow 95 the shaft j to be rocked under the action of its spring. To cause immediate arrestment of the winding-spindle and of the cam-shaft connected therewith, I provide a braking device consisting of the brake m, adapted to engage a disk or collar b on the winding-spindle. The brake m is pivoted on an arm extending from the hub of the lever J and is preferably 100 formed with one or more wedge-shaped

grooves (see Fig. 2) adapted to pinch upon the correspondingly-shaped rim of the disk *b*.

In order that the operation of the machine may be arrested upon the breaking or running out of the supply, I provide a stopping-lever *K*, adapted to release the detent of the starting-lever *J*. The lever *K* for lightness is preferably formed of wire bent in triangular form and suspended at its apex on the free end of the sector *H*. One leg *k* of the lever *K* is made heavier than the others by coiling the wire of the base-piece about it and is formed at its extremity with a bearing-bar *k'* for the thread, terminating in the curved hook *k*². This bearing-bar *k'* hangs adjacent the top of the tension device *L* and is adapted to be supported on the thread as it leads to the thread-guide. The other leg *k*³ is reinforced at its extremity by bending back the wire a short distance before carrying it across to the leg *k*. The tension device is of the usual form, having two opposed plates with alternating parallel bars bearing on the thread to sinuate its course. One of the plates *o* is movable to adapt it to swing toward the other fixed plate, and both plates are supported by a rod *P*, passing through ears at their extremities, the fixed plate being held rigid by the screw *q* and the movable plate hinged on the rod. The rod *P* is bent at its upper extremity in a semicircular form (see Fig. 5) to form a guide for threading the supply under the bearing-bar *k'* and terminates in a loop *p*, passing around the bar *k'* to serve as a limit to the movement of the latter.

The cam-shaft *C* carries a disk *c* at its outer end, the latter formed with a corrugated or fluted rim and rotating in the direction indicated by the arrow. When the lever *K* is supported by the thread, as shown in Fig. 1, the leg *k*³ of the lever hangs adjacent the face of the disk *c*; but when the thread breaks or runs out the weight of the leg *k* carries the extremity of the leg *k*³ into engagement with the disk and the rotation of the latter moves the lever *K* bodily upward, raising the sector *H* and releasing the lever *J*.

In order that the relation of the lever *K* to the disk *c* may be such as to cause a quick and positive action of the stopping devices, I provide means for adjusting the fulcrum of the lever on the sector *H*. As shown in Fig. 3, the lever *K* is supported on a pivot-pin *i*, screwed into the head *i*³ of the stud *i*², the stud *i*² screwing into the end of the sector *H*. The pivot-pin is arranged eccentric to the stud and the head of the latter is knurled to adapt it to be grasped by the fingers. When the stud is turned slightly, the pin is moved toward or away from the disk *c* to adjust the lever *K* in relation thereto. A check-nut *i*⁴ is provided to screw against the sector to secure the stud in position.

In machines of this class it is desirable to have a stop to operate when the cop or pack-

age has reached its predetermined diameter. For this purpose I provide the member *R*, adjustable along the sector *H* and having a beveled under surface which is engaged by a portion of the traverse-frame *E* to lift the sector and release the detent of the lever *J*. The member *R* is preferably formed of sheet metal bent in the form shown in Fig. 4, with a hooked extension reaching up in the groove of the sector *H* and bearing on the bottom. To secure the member in position on the sector, I provide the following novel means: A thumb-screw *r* engages the upper bent portion of the member *R* and is bored to receive the plunger *r'*. This latter is formed with a head *r*², fitting the larger section of the bore of the screw *r*, and with a shank extending through the smaller bore for a bearing and riveted at its end to prevent displacement. Surrounding the shank of the plunger is a coiled spring *r*³, bearing on the bottom of the bore and the head *r*² and tending to force the plunger down on the sector *H*. The upper face of the sector is provided with a shallow groove *h*⁴, and the end of the plunger *r'* is of rectangular form to adapt it to fit the groove. The pressure of the spring *r*³ causes friction between the plunger and the sector *H*, and this slight resistance renders the member more susceptible to fine adjustment. The member *R* may be moved the slightest degree with utmost precision and owing to the frictional contact will remain stationary until set against the sector *H*. This is accomplished by screwing the screw *r* through the member, the lower end of the screw bearing on the shoulder formed by the rectangular end of the plunger and binding the latter in the groove *h*⁴.

The operation of the machine is as follows: The thread is drawn from the supply up through the tensions, carried over against the curved guide portion of the rod *P*, and bearing against the latter is directed under the bearing-bar *k'*. Thence it is led up through the eye of the thread-guide and secured to the winding-spindle, the traverse-frame being placed in position for the guide to bear on the spindle. To start the winding, the lever *J* is swung in the opposite direction from that indicated by the arrow until the lug *l* engages the shoulder *h*², Fig. 1. The swinging of the lever *J* releases the brake from the disk *b* and through the arrangement at the back of the machine causes the driving-pulley to engage the spindle *B* to rotate the latter, which through suitable connections also drives the cam-shaft *C*. The lever *K* is supported in the position shown by the thread passing under the bar *k'*; but when the thread breaks or runs out the lever is released, allowing the extremity to engage the disk *c*, which carries it upward to release the arm *l*. When the arm *l* is released, the spring connected to the shaft *j* rocks the latter to disengage the driving-pulley from its clutch, and the brake

m is brought down on the disk *b*. The member *R* is adjusted on the sector *H* to a point where the frame *E* engages it when the cop has reached a predetermined size. Now as each subsequent cop is wound when it reaches a diameter equal to that of the first cop the traverse-frame *E* will engage the stop *R*, and thereby raise the sector *H* to release the detent of the starting-lever to stop the machine. In this way the machine once set will wind as many packages of the same dimensions as desired.

Automatic stopping devices have before been designed to operate in connection with winding-machines, and I do not here claim the combination broadly; but what I do desire to secure protection for is the particular form and arrangement of mechanism disclosed herein.

20 I claim—

1. The combination in a winding-machine with a winding-spindle, a reciprocating guide, and a swinging traverse-frame to support the guide, of a starting-lever and a sector engaging the traverse-frame to resist its movement toward the winding-spindle and also operating as a detent to retain the starting-lever in position during the operation of the machine.

2. The combination in a winding-machine with a winding-spindle, a reciprocating guide, and a swinging traverse-frame to support the guide, of a starting-lever, a sector engaging said lever to retain it in position to cause the operation of the machine, and a detent on the traverse-frame engaging the sector to resist the movement of the frame toward the winding-spindle.

3. The combination in a winding-machine with the main frame *A*, winding-spindle *B*, thread-guide *D* and traverse-frame *E* for supporting the guide, of a starting-lever *J*, a sector *H* pivoted on the frame *A* to engage the starting-lever to retain the latter in position to cause the operation of the machine, and a detent formed with a **V**-shaped groove, and a detent *e* on the traverse-frame formed with a wedge-shaped extremity engaging the groove in the sector.

4. The combination in a winding-machine with the main frame *A*, winding-spindle *B*, and thread-guide *D*, of a starting-lever *J*, formed with an extension *l* with a lug *l'*, and a sector *H* pivoted on the frame *A*, and having an extension-bearing on the lug *l'* to support the sector and a shoulder *h*² to engage the lug.

5. The combination in a winding-machine with a winding-spindle, a reciprocating thread-guide, and a traverse-frame supporting the guide to swing away from the spindle, of a spring-operated starting-lever, a sector arranged to resist the movement of the traverse-frame toward the spindle and engaging the starting-lever to retain it in position to cause the operation of the machine, and a stopping-

lever pivoted to the said sector and adapted to move the latter to release the starting-lever.

6. The combination in a winding-machine with the main frame *A*, winding-spindle *B*, thread-guide *D*, cam-shaft *C*, traverse-frame *E* pivoted on the cam-shaft, and a starting-lever *J*, of a sector *H* pivoted on the frame *A* and engaging the frame *E* to resist the movement of the latter toward the winding-spindle, and acting as a detent to retain the starting-lever in position during the operation of the machine, a wheel *c* rotating with the cam-shaft and formed with a corrugated periphery, and a stopping-lever *K* pivoted on the sector *H* and adapted to be supported on the running thread and when released by the thread to engage the wheel *c* to tilt the sector *H* to release the lever *J*.

7. The combination in a winding-machine with a winding-spindle *B*, and a reciprocating guide *D*, of a spring-actuated rock-shaft *j*, a starting-lever *J* on the rock-shaft, a detent to retain the lever in position to cause the operation of the machine, a brake-disk *b* on the spindle *B* formed with a plurality of **V**-shaped flanges and a brake-shoe connected with the rock-shaft and adapted to engage the brake-disk *b* when the starting-lever is released from its detent.

8. The combination in a winding-machine with a main frame *A*, winding-spindle *B*, reciprocating guide *D*, and traverse-frame *E*, of a rock-shaft *j*, a starting-lever *J* on the rock-shaft, a sector *H* serving as a detent for the starting-lever and arranged to resist the movement of the traverse-frame toward the spindle and a brake *m* operated by the rock-shaft to arrest the rotation of the spindle on the release of the lever *J*.

9. The combination in a winding-machine with a winding-spindle *B*, thread-guide *D*, and traverse-frame *E*, of a lever *J*, a sector *H* arranged to resist the movement of the traverse-frame toward the winding-spindle and forming a detent for the lever *J*, a stopping-lever *K* pivoted on the sector *H*, and normally supported by the running thread, a rotating disk *c* adapted to engage the lever *K* when the latter is released by the thread, and means for adjusting the lever *K* in relation to the disk *c*.

10. The combination in a winding-machine with a winding-spindle *B*, and thread-guide *D*, of a lever *J*, a detent to retain the lever *J* in position to cause the operation of the machine, a stopping-lever *K* fulcrumed on the detent, a rotating disk *c* to engage the said lever *K* to release the detent, and means to adjust the fulcrum of the lever *K* in relation to the disk *c*.

11. The combination in a winding-machine with a winding-spindle, and a reciprocating thread-guide, of a lever, a detent for said lever, a stopping-lever for releasing said detent, and means for fulcruming the stopping-

lever on the detent consisting of a pivot-pin for the lever and a stud formed eccentric thereto and engaging the detent.

12. The combination of a starting-lever for 5 winding-machines, a detent therefor, a stopping-lever to release said detent, and a fulcrum for the stopping-lever formed with a stud engaging the detent and having a knurled head and a pivot-pin disposed eccentric to the 10 stud.

13. A stop-lever of wire having two legs at an angle to each other, bent to form a coil connecting the two legs, one leg bent back on itself and extended to the other leg and terminating in a coil inclosing the latter leg, which latter leg extends beyond said coil and is bent at the end to form a bearing and a hook, substantially as set forth.

14. The combination in a winding-machine 20 with a winding-spindle B, and thread-guide D, of a lever J, a detent H for the lever, a stopping-lever K fulcrumed on said detent and formed with a thread-bearing bar, a tension device comprising two grid members supported to be pressed together and a rod for 25 supporting said members formed at its upper extremity with a guide to direct the thread under the stopping-lever bearing-bar, and having a loop surrounding said bar to limit the 30 movement of the lever.

15. The combination in a winding-machine with a main frame A, winding-spindle B, thread-guide D, cam-shaft C, and traverse-frame E pivoted on the cam-shaft, of a lever 35 J, a sector H serving as a detent for said lever and supported on the frame A concentric with the axis of the traverse-frame, and means adjustable on the sector H to be engaged by the traverse-frame as it swings outward, to move 40 the sector to release the lever J.

16. The combination in a winding-machine with a rotating winding-spindle and reciprocating thread-guide, of a swinging traverse-frame supporting the guide to move away 45 from the spindle, a lever controlling the op-

eration of the spindle and thread-guide, a detent for said lever formed as a sector and supported concentric with the axis of the traverse-frame, and a stop adjustable on the sector and adapted to be engaged by the traverse-frame. 50

17. The combination in a winding-machine with a winding-spindle and reciprocating thread-guide, of a swinging traverse-frame for the guide, a sector supported concentric with the axis of the frame and shiftable to 55 effect the stopping of the machine, a stop slideable on the sector and adapted to be engaged by the traverse-frame to shift the sector and means for clamping the stop to the sector.

18. The combination in a winding-machine of a detent, shiftable to effect the stopping of the machine, an adjustable stop member slideable on the detent, a thumb-screw in said stop member, a plunger sliding in the screw and 60 adapted to be engaged thereby to set the plunger against the detent, and a spring acting to press the plunger against the detent when the screw is released.

19. The combination with a detent for the 70 starting and stopping devices of a machine, formed with grooves extending longitudinally along its two opposite faces, of a stop R formed with an extension bottoming in one of the grooves, a thumb-screw r in the stop 75 having a central bore, a plunger r² with a rectangular head fitted to the other groove, said head adapted to be engaged by the end of the screw to bind it in the groove, and a spring r³ acting on the plunger to press the 80 latter against the detent when the screw is released.

In testimony whereof I have signed my name to this specification in the presence of two subscribing witnesses.

SIMON W. WARDWELL.
